GIRDLE

Carl R. Glines, Dover, Del., assignor to Sarong, Inc.,
Dover, Del., a corporation of Delaware

Filed Oct. 10, 1963, Ser. No. 76,931

Term of patent 14 years

(Cl. D20—2)

The figure is a front elevational view of a girdle showing my new design, the rear thereof being conventional.

The dominant feature of my design resides in the combination of a double loop dependent from the waist portion thereof with a rose-shaped figure centrally positioned above the loop as shown on the drawing.

I claim:

The ornamental design for a girdle, as shown and described.
